CLAIM

The ornamental design for a vehicle brake friction pad, as shown and described.

DESCRIPTION

FIG. 1 is a perspective view of the vehicle brake friction pad; FIG. 2 is a front view thereof;

FIG. 3 is a top plan view thereof;

FIG. 4 is a bottom plan view thereof;

FIG. 5 is a left side elevation view thereof; and,

FIG. 6 is a right side elevation view thereof.

The broken lines shown in the drawings depict an illustrative brake pad backing plate that forms no part of the claimed design. And the markings depicted on the surfaces of the vehicle brake friction pad denote a friction material.
